UNITED STATES PATENT OFFICE.

JOHN S. WRIGHT, JR., OF CHURCHLAND, VIRGINIA.

BARREL-MACHINE.

SPECIFICATION forming part of Letters Patent No. 664,205, dated December 18, 1900.

Application filed January 16, 1900. Serial No. 1,639. (No model.)

To all whom it may concern:

Be it known that I, JOHN S. WRIGHT, Jr., residing at Churchland, in the county of Norfolk and State of Virginia, have made certain 5 new and useful Improvements in Barrel-Machines, of which the following is a specification.

My invention relates to barrel-making machines, and has for its object a machine of 10 this character especially adapted for making truck-barrels.

The invention consists in certain details of construction and arrangement of the parts, which will be hereinafter specifically 15 described and claimed.

Reference is to be had to the accompanying drawings, in which—

Figure 1 is a side elevation of my improved machine. Fig. 2 is a detail perspective view 20 of the bearing for the former. Fig. 3 is a vertical transverse section of the upper portion of the machine on the line 3 3 of Fig. 1. Fig. 4 is an end view. Fig. 5 is a detail view 25 illustrating one of the intermediate rims of the barrel-form, and Fig. 6 is a perspective view of the barrel-form proper.

My improved machine comprises a standard or base A, suitably supported above the ground or floor and having at each end segmental bearing-plates a, in which friction-rollers a' are mounted. Mounted on the base 30 A is the barrel-form B, which consists of end rims B' and B², U-shaped in cross-section and fitted on the friction-rollers a', with their 35 side flanges overlapping the ends of the rollers, and intermediate rims C and D, both of which are T-shaped in cross-section and of which the rim C has its perpendicular flange C' provided with a series of cogs or teeth, as shown 40 particularly in Fig. 3. All of the rims above mentioned are rigidly connected together by rods E, which extend through the horizontal or base portion of the end rims B' and B² and through the perpendicular annular flanges of 45 the rims C and D, and said rods are arranged alternately, one being connected to the rims C and D and the end rim B', while the next to it is connected to the intermediate rims C and D and the opposite end rim B².

50 Each one of the rims is made in three sections or segments, of which two are connected by hinges or pivots to each end of the inter-

mediate or third one, as shown in Figs. 3 and 5, and the end rims B' and B² are provided at their free ends with a suitable fastening device, which is, as illustrated, a latch B³ on the end of one section adapted for engagement with a pin B⁴ on the opposite end of the other section. In this manner the form B may be thrown open, as illustrated in the detail view Fig. 5, to receive hoops of the barrel when the form is closed, and the latches B³ engage with the pins B⁴ to hold the form in closed position. The barrel-staves and braces are then placed in position inside of 65 the hoops, and the operators nail the staves, and the nails are clenched by their points striking the inner faces of the rims, with each of which a hoop is in alinement.

In order to rotate the form for the purpose 70 of bringing the unfastened staves next to the bed or base of the machine in position for nailing and clenching, I make the rim C with teeth or cogs, as above described, and mount on a suitable shaft secured below the base A 75 a pinion F, meshing with the teeth of said rim, as shown in Fig. 3. On the same shaft I fulcrum the lever G, which is provided with a double pawl G', adapted to engage the pinion F and rotate it and the barrel-form in either 80 direction by the movement of the lever. To depress the lever, a link H is connected thereto and at its other end is secured to a treadle I, which is pivoted to a suitable base-block J. The lever is retracted or raised by a spring 85 K, secured to the side of the base A, as shown in Fig. 3. Now as the work progresses an operator works the treadle with his foot, causing the form to rotate as slowly or rapidly as may be required by the width of the staves 90 used, the object sought being to rotate the barrel-form always into such a position that the nailing of the staves may be effected by driving the nails toward the rigid frame or base upon which the form rests, thereby obviating the tendency of the form to be driven 95 from its bearings.

As illustrated in Figs. 5 and 6, my improved form has important advantages over forms in which the rims are made of two semicircular segments, for it is evident that when the rims of the form are made in three segments, as in my invention, the exertion required for lifting the hinged sections either 100

in opening or closing the form is comparatively insignificant when compared with that required for opening and closing one-half of the heavy form, as would be the case when 5 the rims are made of two semicircular sections, as illustrated in Fig. 6.

Having thus described my invention, what I claim, and desire to secure by Letters Patent, is—

10 In a barrel-making machine, a form comprising end rims U-shaped in cross-section,

intermediate rims formed with perpendicular annular flanges, and connecting-rods passed through the base or horizontal portion of the end rims and through the annular flanges of 15 the intermediate rims, said rods being alternately arranged substantially as shown and described.

JOHN S. WRIGHT, JR.
